(57) **CLAIM**

The ornamental design for a pair of front mudguards of an automobile, as shown and described.

DESCRIPTION

FIG. 1 is a front right of perspective view of a pair of front mudguards of an automobile, showing our new design;

FIG. 2 is a front left perspective view;

FIG. 3 is a rear right perspective view;

FIG. 4 is a rear left perspective view;

FIG. 5 front elevation view;

FIG. 6 is a top plan view;

FIG. 7 is a right side elevation view; and,

FIG. 8 is a left side elevation view.

The broken lines showing environment form no part of the claimed design.
